148,699

DESIGN FOR AN OVERTSHOE OR SIMILAR WATERPROOF ARTICLE

John Eugene Hard, Cranston, R. I., assignor to
Goodyear Footwear Corporation, Providence,
R. I., a corporation of Delaware

Application May 21, 1946, Serial No. 129,932

Term of patent 14 years

(Cl. D7—4)

To all whom it may concern:

Be it known that I, John E. Hard, a citizen of the United States, residing at Cranston, in the county of Providence and State of Rhode Island, have invented a new, original, and ornamental Design for an Overshoe or Similar Waterproof Article, of which the following is a specification, reference being had to the accompanying drawing, forming part thereof.

Fig. 1 is a plan view and Fig. 2 is a front perspective view of an overshoe or similar waterproof article, showing my new design.

I claim:

The ornamental design for an overshoe or similar waterproof article, as shown.

JOHN EUGENE HARD.
